UNITED STATES PATENT OFFICE.

HENRY PALMIERI, OF NEW YORK, N. Y.

IMPROVEMENT IN SUN-SHADES.

Specification forming part of Letters Patent No. 176,675, dated April 25, 1876; application filed April 5, 1876.

To all whom it may concern:

Be it known that I, HENRY PALMIERI, of New York, in the county of New York and State of New York, have invented certain new and useful Improvements in Sun Protectors and Umbrellas; and do hereby declare that following is a full and exact description thereof, reference being had to the accompanying drawings, making a part of this application.

My invention has for its object to provide a shelter from the rays of the sun, or from rain, which may be maintained in position without effort or inconvenience by the wearer; and, with this object in view, my invention consists of an umbrella, or sun-shade, or parasol provided with a suitable frame and securing straps, by means of which it may be adjustably secured to the body of the wearer, and maintained in position, as will be hereinafter more fully set forth.

To enable others to understand the construction and advantages of my improved sun-shade, I will proceed to describe the same, referring by letters to the accompanying drawings, in which—

Figure 1 is a perspective view of a man in the act of fishing provided with my improved sun-shade, and from which it will be seen that, while the wearer is thoroughly protected from the rays of the sun, yet free use of the body and hands is permitted. Fig. 2 is a perspective view of the skeleton or frame of the sun-shade and the supporting-braces and adjusting and securing straps.

A A represent the ribs of the sun-shade, which are formed in about a perfect half-circle, and, preferably, of hoop-skirt wire, pivoted at either end, at 1 1 1, to a hoop, B, of the same material. It will be observed that, from this peculiar construction, the ribs A may be swung upon their pivots 1 1 1 into the position shown in the drawings, to distend the covering; or they may be swung in a reverse direction, to collapse the sun-shade, and lie within the same plane with the hoop B. C is a round-wire brace, pivoted centrally, on opposite sides, to the hoop B at 2 2. This brace is bent to form two eyes, a a, for the purpose presently explained, and is bent upwardly to form a tongue, b, the extremity of which is

bent at right angles to pass through one of several slots, d, in a back brace, D, formed of stiff wire, bent to correspond to the contour or shape of the back, and having loops or eyes e e at the bottom to receive the waistband E, and having its top ends bridged by sheet metal F, through which the slots d before referred to are made. G is a short wire loosely secured to the back center of the hoop B, the loose end adapted to pass through the right-angled end of the tongue b of the brace C, after it shall have passed through one of the slots d, and under a wire loop, f, secured to the brace C at the rear end, through which the back brace D passes, so that when in position shown in the drawings the parts are held in position, and the hoop and sun-shade tilted more or less in either direction by raising or lowering the short wire G, the hoop B rocking on the pivots 2 2. H is a martingale or strap, split at the top, and spread to form straps I I, to connect, slightly forward of the pivots 2 2, to the hoop B, and again split to form straps J J, which connect with the eyes a a. The lower end of the strap H is designed to be secured to a buckle, K, attached by a short strap or otherwise to the waistband E.

It will be observed, from the construction and arrangement of its several parts, that when in the position shown in Fig. 2, and secured to the body of a person, as at Fig. 1, the sun-shade is maintained or supported over the head of the wearer, and that the movement of the limbs and body are not in the slightest degree affected or inconvenienced, and that the sun-shade may be tilted more or less backward and forward on the pivots 2 2, accordingly as the rays of the sun are directed.

I have shown the peculiar construction illustrated in the drawings as preferable on account of lightness and economy; but, of course, the construction may be varied in many particulars without departing from the spirit of my invention. For instance, the frame of the sun-shade may be rigid or collapsible, or fold like any ordinary parasol; and, instead of the peculiar connection shown between the brace C and support D and the short wire G, the brace may be permanently pivoted to the back brace D, and an independent short rod may be loosely connected to the support D, and its

straight upper end passed through a rubber loop or perforated disk or ear attached to the back center of the loop B; or the back wire support, which is fastened to the sun-shade, may be omitted, and have simply two braces, one on either side, with thumb-screws. An independent water-proof cover and cape may be provided, adapted to be secured in place, as seen in dotted lines in Fig. 1, to serve as a protector against rain.

I claim as new and desire to secure by Letters Patent—

1. A sun-shade, provided with the back supporting-brace D/G, side brace C, front martingale-straps, and waistband E, all constructed and arranged substantially as and for the purposes set forth.

2. A frame for supporting the canopy, com-

posed of a series of semicircular ribs, A, and a hoop, B, secured by pivots, in order that the frame may collapse, substantially as and for the purposes hereinbefore set forth.

3. In combination with the brace D, the wire brace C, provided with eyes to receive the martingale-straps, and having the tongue b, substantially as and for the purposes set forth.

4. In a head sun-shade the strap H, split, as shown and described, to form the connecting-straps I I and J J, substantially as for the purpose set forth.

Witness my hand and seal this 24th day of March, 1876.

H. PALMIERI. [L. S.]
